SEWER FLUSHING APPARATUS

Herman Wirz, Jr., and Charles F. Hlavaty, Los Angeles, Calif.

Application February 29, 1932. Serial No. 595,925

5 Claims. (Cl. 137—106)

This invention relates to improvements in sewer flushing apparatus.

The general object of the invention is to provide an improved automatic apparatus for flushing main sewers with fresh water.

Another object of the invention is to provide an automatic sewer flushing apparatus including a water reservoir from which the water is siphoned when the water in the reservoir reaches a predetermined level.

A further object of the invention is to provide novel means for controlling the action of a siphon used in a sewer flushing apparatus.

Other objects and the advantages of this invention will be apparent from the following description taken in connection with the accompanying drawings wherein:

Fig. 1 is a vertical section through our improved sewer flushing apparatus taken on line 1—1 of Fig. 3.

Fig. 2 is a section taken on line 2—2 of Fig. 1.

Fig. 3 is a section taken on line 3—3 of Fig. 1.

Fig. 4 is a view similar to Fig. 3 showing the device before it is completed.

Fig. 5 is an enlarged section taken on line 5—5 of Fig. 1.

Fig. 6 is a top plan view of the parts shown in Fig. 5.

Fig. 7 is a side view of the parts shown in Fig. 5, and

Fig. 8 is a view similar to Fig. 7 showing the various elements in different positions.

Referring to the drawings by reference characters, we have indicated a tank generally at 10. As shown the tank is constructed of concrete and includes a water reservoir portion 12 and a well portion 13. A pipe 14 which communicates with the main sewer (not shown) opens into the well 13. Positioned in the well 13 we provide a branch pipe 15 which includes a single outlet 16 at one end and a pair of parallel inlets 17 and 18 at the opposite end (see Fig. 4). The outlet 16 of the branch pipe 15 communicates with the pipe 14 and the inlet 17 is coaxial with the pipe 14 while the inlet 18 is offset.

Communicating with the inlet 17 we provide a right angle reduction bend 19 the small end of which communicates with a vent pipe 20 which extends upward into the reservoir portion 12 a predetermined distance above the normal water level therein.

Positioned in the well 13 we provide a goose neck pipe 21 which includes two parallel portions 22 and 23 which are joined by a curved portion 24. The portion 22 includes an angular

outlet 25 which communicates with the inlet 18 of the branch pipe 15 and the curved portion 24 is positioned adjacent the bottom of the well 13 while the portion 23 extends upward into the reservoir 12 a predetermined distance. The pipes 14, 15, 19, 20 and 21 are preferably made of clay tile and are secured together by suitable means such as cement in the usual manner.

After the pipes 14, 15, 19, 20 and 21 have been operatively assembled the well 13 is preferably filled in with concrete as indicated at 25 up to a predetermined level where the upper surface of the concrete 25 forms a bottom 26 for the reservoir 12. The upper end of the portion 23 of the goose neck 21 extends above the bottom 26 a short distance.

When the well 13 is filled with concrete a sump 27 is provided in the concrete fill 25. The sump 27 is of a width and depth whereby the inlet end 17 of the pipe 15 is readily accessible therefrom, thus leaving the reduction bend 19 in the open, but embedding the pipes 15 and 21 in the concrete. The top of the sump 27 is adapted to be closed by a plank 28 which is removably supported on metal members 29 embedded in the concrete. The vent pipe 20 extends through the plank 28 and around the pipe 20 and at the top edges the plank 28 is preferably beveled to provide a groove in which a suitable calking material 30, such as melted sulphur is positioned to form water tight joints (see Figs. 2 and 3).

Within the reservoir 12, we provide a siphon head 32 which includes an outlet 33 which at its lower end communicates with the portion 23 of the goose neck 21. The upper portion of the outlet leg 33 is curved at right angles and communicates with an enlarged chamber portion 34 from the bottom of which a reduced inlet leg 35 extends downward to a point spaced a slight distance above the reservoir bottom 26. The siphon head 32 is also preferably made of clay tile and for supporting the siphon head we provide a bracket in the concrete 25 and a crotch portion 38 in which the chamber portion 34 of the siphon head is positioned.

Positioned over the chamber portion 34 of the siphon head and secured to the crotch portion 38 of the bracket by a plurality of bolts 39 we provide a clamping band 40.

For regulating the actuation of the siphon action we provide a control device which we have indicated generally at 45 and shown in detail in Figs. 5 to 8 inclusive. As shown the control device includes a metal pipe nipple 46 having a threaded shank 47 and an enlarged head 48.

The head 48 is positioned against the underside of the clamping band 40 and the shank 47 is positioned in an aperture 49 provided in the band 40 and a nut 50, positioned on the threaded shank 47, securely clamps the nipple 46 to the band 40.

When the band 40 is positioned on the chamber portion 34 of the siphon head the nipple head 48 is positioned in an aperture 51 provided in the top of the chamber portion 34 and a cement 52 which is positioned in a countersunk recess 53 surrounding the aperture 51 provides an air tight seal around the head of the nipple.

Secured to the nipple 46 by threaded engagement with the threaded shank 47 we provide a coupling member 54 and extending upwardly from the coupling we provide a valve device 55.

The valve device 55 is of standard make and includes a chamber 56 having an outlet 57, an inlet 58 and a cylinder portion 59. The inlet 58 communicates with the interior of the coupling member 54 and between the inlet and the chamber 56 a valve seat 60 is provided. Positioned in the cylinder portion 59 a plunger 62 having an enlarged head 65 thereon to which a closure member 64 is secured. The closure member 64 is made of rubber and in a lower position is adapted to engage the valve seat 60 to restrict the passageway from the inlet 58 into the chamber 56 and in a raised position is adapted to allow unrestricted passageway from the inlet 58 through the chamber 56 to the outlet 57.

According to our invention a pair of arms 65 are pivotally mounted on the cylinder portion 59 intermediate their lengths as at 66. One end 35 of the arms 65 terminate in a clamping portion 67 which supports a socket member 68 and the opposite ends of the arms 65 are pivotally connected to a yoke member 69 which is positioned in a slot 70 in the plunger 61. Thus when the 40 socket member 68 is moved downward the yoke 69 will raise the plunger 61 and when moved upward will move the plunger 61 downward.

Supported in the socket member 68 we provide a rod 71. Removably and adjustably clamped to the coupling member 54 we provide a bracket 72 which includes an abutment portion 73 having a reduced stud shaft 74 extending therefrom which terminates in a reduced threaded end portion 75.

50 Rotatably mounted on the stud shaft 74 we provide a disc 76 which is preferably made of a good grade of hard rubber. The disc 76 is mounted on the shaft 74 above the center of the disc and is adapted to be retained on the shaft 74 by a washer 78 and a plurality of nuts 79 positioned on the threaded portion 75 of the shaft. In the outer periphery of the disc 76 we provide a shallow notch 80 and a deep notch 81 defined by a steep end wall 82 and an angular end wall 83.

60 Secured to the face of the disc 76 by screws 84 we provide a metal plate 85 which includes spaced flanges 86 and 87 which are arranged at right angles to the face of the disc and each of which includes an elongated slot or aperture 88.

65 Loosely positioned in the apertures 88 we arrange a rod 89 on one end of which we provide a float member 90. At the end of the rod 89 opposite the float member 90 we provide a threaded section 91 on which is positioned a washer 92 and 70 nuts 93 which are adapted to retain the rod in position on the flanges 86 and 87. Secured to the disc as by screws 94 we provide a weighted member 95.

75 When the water level in the reservoir 12 falls below a predetermined level the weight of the

float 90 and the rod 89 move the disc 76 to the position shown in Fig. 7, wherein the rod 71 is positioned in the shallow notch 80, and retained in a raised position, thus retaining the valve closure 64 in engagement with the valve seat 60. 80 The relation of the disc 76 to the rod 71 is such that when the rod 71 is in a raised position the valve closure 64 is compressed to a predetermined extent thereby applying a tension to the rod 71 which prevents the disc 76 from accidentally turning when the weight of the float is released therefrom as the water rises in the reservoir 12. 85

As the water in the reservoir 12 rises the float 90 and the rod 89 rise with it without disturbing the disc 76 until the rod 89 reaches the position indicated by the broken line 96 in Fig. 7. Upon further upward movement of the float the rod 89 rotates the disc 76 in the direction indicated by the arrow A in Fig. 7.

90 As the disc is thus rotated the rod 71 is forced up and out of the shallow notch 80 and upon continued movement of the disc enters the deep notch 81 and falls downward, thereby raising the valve closure 64 out of engagement with the valve seat 60 (see Fig. 8). When the rod 71 100 enters the notch 81 and the pressure of the rod 71 on the disc 76 is released the weighted member 95 rotates the disc 76 faster than would the rod 89, thereby producing a quick opening of the valve when the water in the reservoir has reached 105 a predetermined point.

110 For filling the reservoir 12 with water we have shown a standard type of metering valve 97 such as is now commonly used in sewer flushing devices and which is connected with a suitable source 110 of water supply by a pipe 98. In operation the metering valve 97 is opened sufficiently to allow a predetermined amount of water to flow into the reservoir 12 in a given length of time.

115 In operation both the portions 22 and 23 of the goose neck 21 are filled with water up to the level of the branch pipe 15 as shown in Fig. 1. As the level of the water in the reservoir rises it moves the float 90 upward as previously described and at the same time water moves upward in 120 the leg 35 of the siphon head 32. As the water rises in the leg 35 of the siphon head the air in the siphon head and goose neck between the water level in the leg 35 and the goose neck leg 23 is compressed and the float 90 is arranged so 125 that it will rotate the disc 76 to operate the valve 55 to an open position slightly before the compression of the air overcomes the weight of the water in the goose neck.

130 The compressed air in the siphon head and goose neck leg 23 also retains the water level in the siphon leg 35 below the water level in the reservoir 12. When the valve 55 is actuated to an open position as previously described the compressed air rushes out through the valve 55, 135 whereupon the weight of the water in the reservoir 12 forces the water in the leg 35 upward and into the siphon leg 33 and the goose neck leg 23 whereupon the water flows into the branch pipe 15 and thence into the pipe 14 from which it 140 flows into the main sewer. After the water has started to flow all the water in the reservoir is siphoned therefrom and discharged through the pipe 14 into the sewer.

145 As soon as the air pressure is released in the siphon head and the water level in the reservoir begins to lower the float 90 moves downward and immediately rotates the disc 76 in a direction opposite to that indicated by the arrow A in Fig. 7, thereby forcing the rod 71 up and out of the 150

deep notch 81 and into the shallow notch 80 thereby closing the valve 55.

The speed with which the water rushes through the branch pipe 15 draws air downward through 5 the vent pipe 20. This air is drawn into the sewer with the water. Thus every time the flushing device is actuated a supply of fresh air is admitted to the sewer thereby diluting the gases formed in the sewer and lessening the danger of 10 sewer gas explosions.

When the flushing device is not actuating to flush the sewer, gases formed in the main sewer can back up through the pipe 14 and the branch pipe 15 and pass out through the vent pipe 20.

15 When it is desired to swab out the pipe 14 the plank 28 is removed, the sealing compound cementing the reduction bend 19 to the branch pipe 15 is melted out and the reduction bend removed from the pipe 15. After that a swab 20 secured to the usual cleanout rods may be inserted from the sump 27 through the branch pipe 15 into the pipe 14.

From the foregoing description it will be apparent that we have provided a novel sewer flushing 25 device which is simple in construction and highly efficient in use.

Having thus described our invention, we claim:

1. In combination with a sewer flushing apparatus including a water reservoir and a pipe positioned below said reservoir and communicating with a sewer, a branch pipe including an outlet at one end and a pair of inlets at the opposite end, said inlet and said outlets having their axes horizontally arranged, said branch pipe outlet 30 communicating with said first pipe, means to conduct water from said reservoir to one of said inlets of said branch pipe and a vent pipe communicating with said other branch pipe inlet.

2. In combination with a sewer flushing apparatus including a water reservoir and a pipe positioned below said reservoir and communicating with a sewer, a branch pipe including a single outlet at one end and a pair of inlets at the opposite end, said inlet and said outlets having their axes horizontally arranged, said branch pipe outlet 45 communicating with said first pipe, one of said branch pipe inlets being in line with said outlet and the other being offset from said outlet and means to conduct water from said reservoir to said offset inlet of said branch pipe.

3. In combination with a sewer flushing device including a water reservoir and a pipe positioned below said reservoir and communicating with a sewer, a branch pipe including a single outlet at one end and a pair of inlets at the opposite end, said inlets and said outlets having their axes horizontally arranged, said branch pipe outlet communicating with said first pipe, one of said branch pipe inlets being in line with said outlet and the other being offset from said outlet, means to conduct water from said reservoir to said offset inlet of said branch pipe, a vent pipe, said vent pipe communicating with said other branch pipe inlet and extending upward above the normal water level in said reservoir.

4. In a sewer flushing device, a water reservoir,

a pipe positioned below said reservoir and communicating with a sewer, means to conduct water from said reservoir to said pipe, said means including a goose neck pipe member and a siphon head, said goose neck member including an outlet leg and an inlet leg joined by a curved portion, said outlet leg terminating in an angular outlet portion communicating with said first pipe, the curved portion of said goose neck being positioned below the plane of said first pipe, said siphon head including an outlet leg, an enlarged transverse chamber portion and an inlet leg, the lower portion of said siphon head outlet communicating with said goose neck inlet leg and the upper end of said siphon head communicating with said chamber, the lower end of said siphon inlet leg being spaced above the bottom of said reservoir and the top of said siphon head inlet leg communicating with said chamber, means to fill said reservoir with water, said chamber having an air inlet, a valve for controlling said inlet, said valve including an operating member, a pivoted disc, a float for swinging said disc, said disc having portions thereon for engaging said operating member to move the latter whereby when the water level 80 in said reservoir rises above a predetermined point the air in said siphon head will be released to the atmosphere.

5. In a sewer flushing device, a water reservoir, a pipe positioned below the bottom of said reservoir, a branch pipe positioned below the bottom of said reservoir, said pipe including a single outlet at one end and a pair of inlets at the opposite end, a reduction bend pipe communicating at its large end with one of said branch pipe inlets, a vent pipe communicating with the small end of said reduction bend and extending upward to a point above the normal water level in said reservoir, a goose neck pipe member including an outlet leg and an inlet leg joined by a curved portion, 105 said outlet leg terminating in an angular outlet portion communicating with said other inlet of said branch pipe, the curved portion of said goose neck being positioned below said branch pipe, said inlet leg of said goose neck extending upward into 110 said reservoir, a siphon head including an outlet leg, an enlarged chamber portion and a reduced inlet leg, the lower portion of said outlet leg of said siphon head communicating with said inlet leg of said goose neck and the upper end of said 115 siphon head outlet leg communicating with said chamber, the lower end of said siphon head inlet leg being spaced above the bottom of said reservoir and the top of said siphon leg communicating with said chamber, a valve member communicating with the interior of said chamber, a float for actuating said valve member, said valve when 120 said float is in a lowered position below a predetermined point being closed and when said float is in a raised position above a predetermined point 125 being in an opened position to allow free passage-way of air from said chamber through said valve to the atmosphere.

HERMAN WIRZ, JR. 140
